RELAY SYSTEM

Winfield R. Koch, Camden, N. J., assignor to
 Radio Corporation of America, a corporation
 of Delaware

Application March 1, 1934, Serial No. 713,621

7 Claims. (Cl. 250—36)

My invention relates to thermionic or electric discharge tube utilization networks analogous to the one shown on page 167 et seq., volume 2, textbook on Wireless Telegraphy, (British) by Rupert

5 Stanley, 1923 edition.

More particularly, the invention relates to relay systems wherein thermionic or electric discharge tubes are utilized as "triggered" controlling elements for operating current responsive 10 and other electrical devices connected in circuit therewith. In a specific form of the invention, a multi-vibrator type of circuit is employed for the purpose of providing a relay circuit having the characteristics of an amplifier and certain characteristics of a multi-vibrator.

15 Heretofore, the multi-vibrator, so called as exemplified by the publication referred to, has been utilized principally for the production of oscillations rich in harmonics. Insofar as I am aware, 20 however, the multi-vibrator or an equivalent circuit has not been utilized as direct-connected amplifier or as a relay of the so-called "trigger" type.

25 Furthermore, the conventional multi-vibrator is somewhat disadvantageous in that it requires a high plate potential source and, by reason of the fact that the frequency of oscillation thereof is determined by variable condensers inter-connecting the plate of one tube with the grid of the 30 other, its frequency stability may be somewhat affected by changes in atmospheric conditions.

35 It is, accordingly, an object of my invention to provide an amplifier of the direct-connected type that shall not require a high potential plate supply source, and coupling condensers between inter-connected anodes and grids while maintaining a high degree of stability.

Another object of my invention is to provide 40 an amplifier or relay of the trigger-action type, the output current from which need not necessarily be proportional in amplitude to the input potential applied thereto.

Another object of my invention is to provide 45 a relay of the type referred to wherein the duration of the output current is independent of the duration of the input potential.

Another object of my invention is to provide, 50 in a relay of the type referred to immediately above, means whereby the said relay automatically returns to normal condition upon removal of input potential.

Another object of my invention is to provide a 55 trigger relay of the type referred to that shall have an output current which goes through a definite cycle in response to a change in input

potential and automatically returns to normal value.

Another object of my invention is to provide a trigger relay that shall be responsive only to input potentials having a predetermined duration. 5

Another object of my invention is to provide an oscillator of the multi-vibrator type, characterized by the fact that from the output circuits of the several tubes included therein wave-forms having differing frequency characteristics may be 10 obtained.

A still further object of my invention is to provide an oscillator of the type referred to that shall be capable of oscillating more strongly than oscillators of conventional multi-vibrator types, and 15 with greater stability.

The foregoing objects and other objects ancillary thereto I accomplish in preferred embodiments of my invention through the use of electric discharge devices or tubes of the so-called 20 screen grid pentode type known commercially as RCA—57, RCA—58 and the like.

The novel features that I consider characteristic of my invention are set forth with particularity in the appended claims. The invention itself, however, both as to its organization and its method of operation, together with additional objects and advantages thereof, will best be understood from the following description of a specific embodiment, when read in connection with 30 the accompanying drawing, in which:

Figure 1 is a schematic circuit diagram of a direct connected electric discharge amplifier for direct current and audio frequency signals down to relatively low frequency values, although high- 35 er frequency signals such as radio frequency signals may be amplified thereby;

Fig. 2 is a similar schematic circuit diagram of a relay circuit embodying two direct connected electric discharge devices arranged for "trigger" 40 control;

Fig. 3 is also a similar diagram of a "trigger" relay provided with means whereby it is self restoring; and

Figs. 4, 5, and 6 are schematic circuit diagrams 45 exemplifying the application of the invention to oscillators of the multi-vibrator type.

Referring to Fig. 1 of the drawing, which is fundamental to the remaining figures, an amplifier constructed according to my invention preferably comprises a plurality of electric discharge devices or tubes 1 and 3 of the so-called screen-grid pentode type. The first tube 1 is provided with an anode 5, a suppressor grid 7, a screen grid 9, a control grid 11, and a cathode 55

13. The second tube 3 is identical in construction and is also provided with an anode 15, a suppressor grid 17, a screen grid 19, a control grid 21, and a cathode 23.

5. The anodes of the several tubes are connected to the positive terminal of a plate potential source over resistors 25 and 27 respectively, the last-named resistor providing the output impedance of the system and being provided with output terminals E₂. The green grid of the first tube, 1, is also connected to the positive lead of the plate potential source and a direct connection 26 extends from the plate of that tube to the screen grid of the second tube, 3.

15. The cathodes of the several tubes are connected together and to the negative terminal of the plate potential source. The control grid 11 of the first tube is connected to the cathode through a grid leak 12 and is provided with input terminals E₁ across said resistor. The control grid 21 of the second tube may be connected to its cathode directly or through a grid leak 22, as shown in the drawing.

It will be noted from an inspection of Figure 1 of the drawing that there is no cross-connection from the plate of the second tube back to the screen grid of the first tube. Such being the case, the operating condition of the first tube is not appreciably influenced by the condition of the second tube, and the system may be utilized as a direct current amplifier or an amplifier for alternating current at any frequency from zero up to a limiting frequency determined by the input capacity of the tube.

35. The operation of the system shown in Fig. 1 is as follows:

Direct current potentials or alternating current signal potentials applied to the input terminals designated at E₁ are applied to the screen grid 19 of the second amplifier stage through the coupling impedance 25 in circuit with the anode 5 of the first amplifier stage.

40. Signals applied to the screen grid 19 are amplified and may be derived from the anode circuit connected with the anode 15 and, in the present example, are taken in parallel with the output impedance 27 from the terminals E₂.

This system has the advantage that since the screen grid 19 and the anode 5 may operate 50 at the same potentials they may be directly connected as shown, whereby the coupling system is reduced to a single impedance device 25 and the usual coupling condenser is eliminated, thereby improving the frequency response. Furthermore, 55 the usual high voltage source of anode potentials or the separate battery source of anode potentials and separate filament supply circuits ordinarily required by the usual D. C. amplifier are not required in the present amplifier system.

60. In the case that an additional stage of amplification is desired, a second amplifier may be connected with the device 3 through the output terminals E₂ in the same manner as the device 3 is coupled to the device 1, through a coupling impedance or resistor in the anode circuit of one device and a direct connection from the anode end thereof to the screen grid of the amplifier device in the succeeding amplifier stage.

70. Referring now to Fig. 2, a pair of electric discharge amplifier devices 30 and 31 of the screen grid pentode type are shown connected in a balanced amplifier circuit similar to that of a multivibrator. In this circuit, however, the devices 30 and 31 do not operate as oscillators but as 75 relays of the "trigger" type. In this type of re-

lay, a change in control grid voltage sets the relay in action to cause a change in anode current from one predetermined value to another.

In the present example, the anode 32 of the device 30 is provided with a coupling impedance 5 33 by which it is coupled through a connection 34 with the screen grid 35 of the second device 31. In a similar manner the anode 36 of the device 31 is coupled back through the impedance 37 and connection 38 with the screen grid 39 10 of the first device 30. The anodes and screen grids of the pair of amplifiers are thus cross connected. Grid leak connections to the cathode are provided for the control grids 40 through grid leak resistors 42 and 43. Likewise, the suppressor grids 41 are connected to the cathodes whereby the same operating potentials may advantageously be used on both anodes and screen grids, thereby permitting a direct connection between amplifiers and common coupling imped- 20 ances.

Signal input terminals 44 are provided in parallel with one of said grid leak resistors 42, while a second pair of signal input terminals 45 are provided in series with the grid leak resistor 43. 25 The latter terminals are short-circuited but may be open-circuited for applying signal potentials to the grid 40.

The output circuits of the devices 30 and 31 30 may be connected to any suitable utilization means and in the present example, the output circuit for the device 31 is connected with a current responsive device such as a relay 46 which is connected in series with the coupling impedance 31 adjacent to the anode 36. A series output circuit is thereby provided for the device 31. 35

However, it is desirable under certain circumstances, to utilize a shunt output connection, which is shown in connection with the device 30, an output circuit therefor being indicated 40 by the leads 47. It will be noted that these leads are connected between the anode and the cathode of the device 30 and that the arrangement is such that the coupling device 33 is utilized as an output impedance for the leads 47. 45

The operation of the relay is as follows:

A small negative signal potential on the input terminals 44 causes a reduction in the anode current of the first amplifier device 30 through the coupling impedance 33. This causes a reduction in the I. R. drop through the impedance and a corresponding increase in the potential on the anode 32 of the first amplifier device 30 and on the screen grid 35 of the second amplifier device 31. The increased screen grid potential 55 causes an increase in the anode current of the device 31 and a corresponding increase in the I. R. drop through the coupling impedance 37.

The latter action results in a reduction of the potential on the anode 36 and on the screen grid 39 and this in turn further decreases the anode current through the impedance 33. This action continues until the anode current to the device 30 is substantially zero and the anode current 60 to the device 31 is substantially maximum when a condition of equilibrium exists in the various circuits. The increased anode current causes the relay 46 to be operated at a predetermined value of current for which the relay is adjusted. 70

It has been found that the action of this relay is extremely rapid and substantially independent of the duration of time of the application of the controlling potential to the input terminals 44 and that the controlling potential need be only 75

slightly negative to start the operation of the relay from the condition above described.

To restore the relay to its normal condition or to reverse the operation above described, a positive potential may be applied to the grid 40 at the terminals 44 or, preferably, a slightly negative potential is applied to the grid 40 of the device 31 whereupon the relay operates to reduce the anode current of the device 31 to substantially zero and to restore it to normal through the device 30.

For the purpose of triggering the relay in either direction to actuate the current responsive device 46 in circuit therewith or to restore the relay system to a normal condition of operation, a source of negative or positive potential 48 may be provided in connection with the grids 40, and this potential may be applied selectively to either of said grids, that is, between grid and cathode 20 of either tube, through a suitable selective switching means 49 and grid potential supply leads 50. From an inspection of the circuit, it will be seen that the switch 49 may be closed in either one of two directions to apply a potential from the 25 source 38 through the leads 50 to a selected one of the grids 40.

The controlling potential for the relay may be applied to the input terminals 45 for the device 31 by removing the short circuit therefrom and the 30 signal output from the relay system may be taken from the output impedance 33 through the output leads 47.

The use of a separate input circuit for each of the devices 30 and 31 has the advantage that the 35 system may be utilized to respond to two different control voltages if applied thereto in proper sequence.

The anode current in one of the devices 30 or 40 31 is always substantially zero and at a maximum in the other. A small negative potential on the grid of the device taking anode current will cause the anode current to suddenly and completely drop to substantially zero and the anode current of the other device to as suddenly and completely 45 increase to a maximum. The relay is therefore of the "trigger" type, but is somewhat different from the usual type in that the change from zero to maximum plate current has no intermediate stopping point and is substantially instantaneous.

50 Relatively low positive potential on the other grid, that is the grid of the device not taking plate current will cause the same result. It has been found that a control potential of less than 1.5 volts, with suitable amplifier devices such as the 55 RCA-57 and RCA-58 tubes will provide a wide change of voltage in the plate resistors, which may be in the order of a hundred or more volts.

By way of example, the coupling resistors or 60 impedances 33 and 37 may have a value of substantially twenty to thirty thousand ohms, while the input coupling impedance or grid leak resistors 42 and 43 may have any desired value, depending upon the impedance of the input circuit and the voltages to be applied to the control 65 grids. The anode potential supply leads indicated at 51 and 52 may be supplied direct current potentials of substantially 250 volts for tubes of the type hereinbefore designated.

70 With the circuit arrangement as above described, it will be seen that the application of a positive potential to the grid of the device in which the plate current is maximum will have no affect upon the equilibrium of the system, whereas the application of even a slightly negative potential thereto will cause the relay to be actuated.

The application of controlling or triggering potentials alternately to the control grid circuits for actuating the relay circuit in alternate directions must therefore occur in a predetermined sequence.

In this circuit also, advantage is taken of the fact that the screen grids of screen grid pentode devices may be connected with the same potential source as the anodes, whereby the anodes and screen grids of the relay device may be interconnected directly without coupling condensers or 10 the like as in the preceding amplifier circuit of Fig. 1. The use of the suppressor grid permits plate voltage to be the same as the screen voltage without a loss of efficiency.

Referring now to Fig. 3, a trigger relay similar 15 to that shown in Fig. 2 is further provided with means whereby it is automatically restored to a normal operating condition upon completion of the operating cycle. In this figure, the circuit connections and circuit elements are substantially the same as in Fig. 2 and bear the same reference numerals.

It will be noted that the amplifier device 31 is provided with signal or control voltage input terminals connected across the grid circuit re- 25 sistor 43 of the device 31 for applying controlling potentials to the control grid 40 of said device. The device 31 is, therefore, the first amplifier in this circuit.

Having selected the device as a first amplifier 30 for receiving the controlling potentials, the second control grid, that is the control grid of the second amplifier device 30 is coupled with the screen grid of the same device, through a coupling condenser. This condenser is shown at 53, 35 connected between the screen grid 39 and the adjacent control grid 40 of the device 30. The specific circuit arrangement is such that the condenser 53 and the grid impedance 42 provide a time delay filter or network in connection with 40 the said second control grid, the first control grid being considered as that selected to receive controlling potentials directly as above indicated.

It will be noted that there is also provided in connection with each of the control grid circuits 45 a source of biasing potential arranged to provide a higher negative bias on one grid than upon the other. In the present example the device 30 is provided with a higher biasing potential from a source, 55 than the corresponding biasing potential obtained from a source 54, for the device 31.

The operation of the system described is as follows:

A short signal impulse applied to the input 55 terminals 56 is applied to the grid of the first amplifier device or tube 31 and causes the relay system to pass through a complete cycle, the length of which depends upon the capacity and impedance values in the time delay network 60 53-42 provided in connection with the second amplifier device 30.

When a negative impulse is applied to the control grid 40 of the device 31 from the signal input terminals 56, the plate current of said device decreases to zero while the plate current of the device 30 increases to a maximum substantially in the same manner as described in connection with Fig. 2. Following this operation, the plate current in the device 31 increases and 70 the plate current in the device 30 decreases, the former becoming maximum and the latter becoming substantially zero whereupon the relay system is restored to normal and is ready for a second control impulse.

The delay in the cycle results from the control effect of the delay network comprising the coupling condenser 53 through which controlling impulses are obtained from the screen grid circuit 38, and the impedance or resistor 42 through which the control grid 40 is connected to the cathode return circuit 51 and bias supply.

The resistor 42 is variable for the purpose of controlling the time delay of the network, and 10 is so adjusted with respect to the capacity of the condenser 53, that the latter is permitted to discharge at a predetermined rate whereby the relay circuit may operate to control a device connected in circuit therewith such as the current 15 responsive device 46.

If the time delay network is connected with the control grid having a less negative bias, then, instead of a relay which may be operated to pass through a predetermined cycle in response to a 20 signal controlling impulse of any duration, an oscillatory circuit is provided, the frequency of oscillation being determined by the impedance of the time delay network.

Such a circuit is shown in Fig. 4 to which attention is now directed, and in which the same reference numerals are applied to like parts as in Fig. 3.

In Fig. 4, the screen grid pentode tubes 30 and 31 are directly interconnected through anode 30 coupling impedances 33 and 37 and grid leads 34 and 38. A relatively higher negative bias is provided by the source 55 for the control grid 40 of the device 30 than is provided by the source 54 for the corresponding control grid of the device 31.

Grid impedances 42 and 43 are provided in the control grid circuits, and the impedance 43 is connected with a coupling condenser 53 to the screen grid lead 34 so that the filter network is provided in connection with the control grid to 40 which the lower negative bias is supplied.

Output terminals are provided as indicated at 58, 59, 60 and 61. The output terminals 58 are in series with the anode 36 of the device 31, adjacent thereto, and between the anode and the coupling impedance 37. The short circuit across the terminals 58 is removed when taking the output therefrom, and one of the terminals 58 and the terminal 59 may be employed for taking the 50 output from the coupling impedance 37 in shunt therewith. If desired, the output energy from the oscillator may be taken from other points in the anode circuit such as from the cathode return lead through the terminals 60, in short circuit being removed for this purpose.

In a similar manner, energy may be taken from the oscillator device 30 as indicated by the terminals 61 provided in the cathode return lead and corresponding to the terminals 60.

It has been found that in operation, in an oscillator device having a time delay network and the lower negative bias source of potential, as in this case for example, the oscillations are substantially rectangular in shape or square topped, while the wave shape of the oscillations in the other device is more generally saw-toothed in form. Therefore, in this type of cross-connected oscillator, wherein the coupling is direct and the control grids are biased at differing potentials, a time delay network may be applied, 70 which permits two differing wave forms to be provided in the generated oscillations.

It has been found that the time delay network may be provided in series with the screen grid 75 circuit as shown in Fig. 5, to which attention is

now directed. The time delay network is provided in the screen grid lead 38 in the form of a variable impedance or resistor 62 and a condenser 63 connected in shunt therewith. This time delay network is connected between the coupling impedance 37 of one amplifier device at the anode end thereof, and the screen grid 39 of the other amplifier device.

The control grids 40 are provided with series impedance elements 42 and 43, and it will be 10 noted that the device 30, with which the time delay network is connected, is provided with a lower negative bias on the control grid. In this case, the bias potential is that of the cathode, while the device 31 is provided with a source 15 54 of low negative potential for the control grid 40.

It has been found that the output from this type of oscillator is steady and its operation is stable over long periods of operation. The output is taken from the output of the anode circuits 20 by any suitable connection such as hereinbefore described and as indicated by the series anode circuit output terminals 58. The use of the suppressor grid in the oscillator and amplifier circuits, as hereinbefore shown and described, materially aids in causing the circuits to operate 25 without setting up undesired oscillations.

It will be seen that in the circuit shown, the suppressor grids are connected with the cathodes. Likewise, the control grids are also connected 30 with cathode through an impedance device to which signals or control potentials may be applied. The signals or potentials are derived either from an external source or from the screen grid 35 circuit. The screen grids are directly connected with the anodes of the balanced pair of amplifiers or oscillator devices for the reason the circuit connections are simplified and the suppressor grids tend to maintain the amplifier devices 40 in stable operation. The control grids are unbalanced by the initial biasing means therefore, in order that the balanced pair of devices may be arranged to operate as a relay or as an oscillator.

The external source of bias potential may be 45 eliminated by utilizing the potential drop in anode circuit impedance devices, such as cathode resistors 64 and 65, as shown in Fig. 6. In this circuit, the control grid of each amplifier or oscillator device is connected through leads 66 50 and 67 with the cathode end of the bias resistor for the other device.

A time delay network is provided in connection with each of the control grids by means of a condenser 68 connected from each control grid 55 to the cathode and a variable series impedance or resistor 69 in each of the control grid leads 66 and 67.

With this arrangement, the varying control potentials, existing across the impedances or 60 cathode resistors 64 and 65, are applied to the control grids through the impedances 69 under control of condensers 68, so that the potential changes on the control grids are relatively slow and may be adjusted by adjusting the value of 65 the impedances 69. The operation is otherwise the same as that for the oscillators shown and described in Figs. 4 and 5 and the same reference numerals are applied to the same parts. The voltage output from each oscillator device 70 is the same, both being rectangular type waves.

An oscillator as shown and described, has the advantage that vigorous oscillations are produced and the signal output is relatively strong. The circuit has the further advantage that cathode 75

lead impedances provide the source of biasing potential for the oscillator.

The voltage or signal output may be taken from the anode circuit of either device, substantially in the same manner as described in connection with the preceding circuits, as from the terminals 58 and 59.

I claim as my invention:

1. In a relay system, the combination of a pair of electric discharge devices each comprising an anode, a cathode, a suppressor grid adjacent to the anode and connected to the cathode, a control grid adjacent to the cathode, and a screen grid between said suppressor and control grids, an anode coupling impedance in circuit with each of said anodes, means providing a connection between each control grid and the cathode, means providing a direct connection between the anode of one device and the screen grid of the other device, a condenser coupling the screen grid of one device to its control grid, a resistor connecting said control grid with the cathode of said device, and means for applying a more negative biasing potential to one of said control grids than to the other.

2. A balanced electric discharge delay circuit, including a pair of screen grid electric discharge amplifier devices conductively interconnected between the cathode of one device and the control grid of the other device and between the anode of each device and the screen grid of each other device, means for stabilizing said circuit including a suppressor grid in each of said devices connected to its cathode, means for applying a differing biasing potential on the control grids of said devices, and a time delay circuit network interconnecting the cathode and two of the grid electrodes including the suppressor grid of one of said devices and the anode of the other device.

3. A relay circuit including two electric discharge devices of the pentode type, a common coupling voltage drop producing impedance connected in circuit with the screen grid of one device and the anode of the other device, said circuit connection with said impedance providing a direct conductive connection between the last named screen grid and anode, the suppressor grids of said devices being connected to their respective cathodes for stabilizing said circuit, means for applying differing biasing potentials to the control grids of said devices, and a time delay circuit network interconnecting the cathode and two of the grid electrodes of said other device and the anode of said one device.

4. An oscillator circuit comprising a pair of electric discharge devices of the pentode type, each having a screen grid interconnected directly with the anode of the other device, a filter net-

work connected between the cathode and control grid of one tube and the cathode and control grid of the other tube, a connection between each suppressor grid and its cathode, a source of potential, and a potential drop producing impedance element in circuit with each cathode through said source to said anodes.

5. A multi-vibrator oscillator comprising in combination a pair of electric discharge devices of the pentode type, means for applying differing negative biasing potentials to the control grids of said device, a potential drop producing impedance element, the screen grid of one device and the anode of the other device being directly coupled through said impedance element, the anode of said one device providing an output connection for said oscillator, a time delay filter comprising a condenser and a resistor connected between the anode of said one device and the control grid of said other device, the resistor being in circuit between the cathode and the control grid of said other device.

6. A trigger amplifier comprising in combination, a pair of electric discharge devices of the pentode type each having a cathode, an anode, a suppressor grid adjacent to the anode and connected to the cathode, a control grid adjacent to the cathode and a screen grid interposed between said suppressor and control grids, means providing a direct connection between each screen grid and the anode of the other device, anode output coupling impedances connected one with each anode, means including an impedance device providing a connection between the control grid and the cathode of each device, means for applying a controlling potential to one of said control grids, means for biasing said grid at a lower negative potential than the control grid of the other device, and a filter network connected with the screen and control grids of said other device and between the cathode thereof and the anode of said one device, said filter network including a variable impedance device.

7. In an electric relay system, the combination of a pair of electric discharge devices of the pentode type, having the anode of one device directly connected with the screen grid of the other device, and each having a suppressor grid and control grid connection with the cathode thereof, means for applying differing negative biasing potentials on the control grids of said devices, means for applying controlling potential impulses selectively to the control grids of said devices, and a time delay circuit network interconnecting two of the grid electrodes of said one of said devices and the anode of said other device.

WINFIELD R. KOCH.
